AIR DRAIN VALVE

Ernst Wiedmann and James K. Douglas, Milwaukee, Wis., assignors to The Oilgear Company, Milwaukee, Wis., a corporation of Wisconsin

Application August 4, 1936, Serial No. 472,929

10 Claims. (Cl. 251—114)

This invention relates to air drains for draining entrapped air or gases from hydraulic circuits.

The air drain to which the invention applies in particular has a restricted passageway, such as 5 a coil of small diameter tubing, through which limited volumes of liquid and air and other gases are forced by hydraulic pressure, and a valve for controlling this passageway to prevent air from entering the circuit when the liquid therein is 10 not under pressure.

The invention is particularly adapted for use in hydraulic circuits in which the hydraulic pressure varies through a wide range, such as the circuits of hydraulically operated machine tools 15 which carry a low pressure when the machine is running idle, a higher pressure when the tool carriage is being operated at rapid traverse speeds and, usually, a still higher pressure when the cutting tool is being fed into or against a piece of 20 work.

If the prior air drains were adjusted to pass the necessary volume of fluid at the low pressures to free a circuit from entrapped air, so large a 25 volume of liquid would escape when the air drain was subjected to a high feeding pressure that the efficiency and control of the machine were seriously affected.

If the passageways in the prior air drains were restricted sufficiently to adequately restrain the 30 discharge of liquid at high pressure, they would become clogged with foreign matter and, if the passageways were large enough to minimize the danger of clogging, they had to be so long that the resultant air drain was large and cumbersome. 35 In any case, the continuous leakage through the air drain during the feeding operation detracted from the accuracy of the feed.

The present invention has as an object to provide an air drain valve which when connected to 40 a hydraulic circuit will permit entrapped air or gas to escape therefrom without affecting the rate of operation of a hydraulic motor connected into that circuit.

Another object is to provide an air drain valve 45 which is fully automatic in operation.

Another object is to provide an air drain valve which is compact and efficient.

According to the invention in its general aspect and as ordinarily embodied in practice, the air 50 drain valve is provided with a casing having an inlet which may be connected to a hydraulic circuit to permit liquid to escape therefrom into the casing and an outlet through which liquid may escape from the casing, the inlet is connected 55 to the outlet through a restricted passage through

which liquid may flow at a predetermined limited rate at a predetermined low fluid pressure, a plunger is fitted in the casing and coacts therewith to close communication between the inlet and the outlet in either of two positions, the plunger is urged toward the inlet and into its initial position by a spring or other force in which initial position of the plunger communication between the inlet and the passage is kept closed until there is created in the circuit a predetermined low fluid pressure which overcomes the initial resistance of the spring or other force and moves the plunger out of its initial position to permit liquid to flow through the passage at a limited rate. 10

The liquid may continue to flow through the passage at the limited rate until either the pressure in the circuit drops sufficiently to permit the spring or other force to return the plunger to its initial position and close the inlet to the restricted 15 passage to prevent air from entering the circuit or until there is created in the circuit a pressure which is enough higher than the low pressure to move the plunger farther from the inlet and into a position to again close communication between 20 the inlet and the outlet and thereby prevent liquid from escaping from the circuit through the air drain valve at the higher pressure.

The invention is exemplified by the air drain valve illustrated in the accompanying drawing in 25 which the views are as follows:

Fig. 1 is a central vertical section showing the valve closed to prevent the admission of air into a hydraulic circuit.

Fig. 2 is in part an elevation and in part a 35 central section showing the valve closed to prevent the escape of fluid from a hydraulic circuit.

The air drain valve has a casing which, preferably, is formed of a cylinder 1 having a longitudinal bore 2, a head or cap 3 for closing the upper 40 end of bore 2 and having an outlet 4 communicating therewith, and a plug 5 for closing the lower end of the bore 2 and having an inlet 6 communicating with the bore.

The head 3 and the plug 5 are connected to the 45 cylinder 1 to make an oil tight seal therewith, as by the head 3 being threaded into the upper end of the bore 2 and provided with a shoulder 7 to abut the end of the cylinder 1, and the plug 5 being threaded on the lower end of the cylinder 1 50 into engagement with a shoulder 8 formed thereon.

The cylinder 1 contains a plunger 9 which is slidably fitted in the bore 2 and provided upon its periphery with a spiral groove 10 through which 55

limited volumes of liquid and air or other gas may pass from the inlet 6 to the outlet 4.

The groove 10 ordinarily extends around the plunger 9 throughout the greater part of the length thereof, to provide a long restricted passage through which liquid may flow only at limited rates, but it stops at a point short of the lower end of the plunger to provide an ungrooved portion which coats with the wall of the bore 2 to close communication between the inlet and the outlet when the plunger is raised a sufficient distance, as shown in Fig. 2. The ungrooved portion of the plunger thus functions as a valve for controlling the escape of liquid through the outlet 4 from any hydraulic circuit to which the air drain valve may be connected.

The bore 2 is enlarged at its lower end, as shown in Fig. 1, to provide a counterbore with which the groove 10 communicates when the plunger is in a lower position. Liquid may flow from the inlet through the counterbore into the groove and out of the groove into the outlet from the time that the plunger is raised slightly from the position shown in Fig. 1 until the ungrooved portion extends above the counterbore as shown in Fig. 2.

The flow of fluid from the bore 2 into the outlet 4 is secondarily controlled by a valve 11 which is carried by the upper end of the plunger 9 and adapted to engage a valve seat 12 which is arranged upon the inner end of the head 3 and surrounds the outlet 4.

The flow of fluid from the bore 2 into the inlet 6 is controlled by a valve 13 which is carried by the lower end of the plunger 9 and adapted to engage a valve seat 14 which is arranged upon the inner surface of the plug 5 and surrounds the inlet 6.

The plunger 9 is urged downward by a helical compression spring 15 which has its lower part arranged in a bore 16 formed in the plunger 9 and its upper part extended into the head 3 into engagement with a washer 17 arranged therein.

The air drain valve is ordinarily connected into a hydraulic circuit at a high point therein and is provided upon the lower end of the plug 3 with threads 18 for engagement with the thread of a pipe fitting 19 or other part of a hydraulic circuit.

When a predetermined low pressure has been created in a hydraulic circuit to which the air drain is attached, liquid will enter the inlet 6 and exert sufficient force upon the bottom of the plunger 9 to raise it against the resistance of the spring 15 and thereby open the valve 13.

As air or other gas entrapped in a hydraulic circuit will work its way to the high points in the circuit, the liquid entering the air drain valve will carry entrapped air or other gas with it, and limited volumes of liquid and entrapped air or gas will flow through the groove 10 and escape through the outlet 4.

An increase in the pressure in the hydraulic circuit causes an increase in the rate of flow through the groove 10 which is sufficiently large in diameter to avoid practically all danger of clogging and of sufficient length to provide the resistance required to limit the volume of escaping liquid to a predetermined maximum, for instance, 20 cu. in. per minute under a pressure of 125 pounds per square inch in the hydraulic circuit. In actual practice, the cross-sectional area of the groove 10 does not exceed .012 sq. in.

An increase in pressure in the hydraulic circuit also causes the plunger 9 to rise and thereby increase the resistance of the spring 15 which holds the valve open until the pressure reaches a

predetermined maximum and then the ungrooved portion of the plunger 9 enters the unenlarged part of the bore 2 and prevents further escape of liquid through the groove 10. A further rise in pressure will cause the valve 11 to close and thereby provide a second seal between the inlet and the outlet.

When the pressure in the circuit falls sufficiently, the spring 15 urges the valve 13 to its seat to prevent air from entering the circuit 10 through the air drain valve.

The plunger 9 is thus reciprocated as the pressure rises and falls in the circuit to which the air drain valve is attached and thereby causes relative movement between the several turns of the 15 groove 10 and the wall of the bore 2.

Particles of foreign matter carried by the liquid in the groove 10 are thus rubbed against the wall of the bore 2 and either broken up or rolled along the groove 10, thus allowing a smaller passageway to be employed than if the parts forming the passageway were wholly stationary.

The tension of the spring 15 may be varied in accordance with the requirements of the hydraulic circuit in which the air drain is to be employed, but it is found in practice that the circuits of practically all types of hydraulically operated machine tools are freed from entrapped air by employing an air drain valve having a spring 15 which will keep the groove 10 open until the pressure in the circuit reaches from 75 to 125 pounds per square inch and then allow it to be closed, and which will close the valve 13 when the pressure in the hydraulic circuit falls below five pounds per square inch.

Entrapped air may thus drain from the circuit during the entire period that the machine is running idle and, in many circuits, during the time that the machine is operated at rapid traverse speeds but the escape of relatively large volumes of liquid is effectively prevented when the circuit is carrying high feeding pressures, thereby freeing the circuit from entrapped air without affecting the efficiency of the control of the machine.

The invention herein set forth is susceptible of 45 various modifications and adaptations without departing from the scope thereof as hereafter claimed.

The invention is hereby claimed as follows:

1. An air drain valve, for connection into a hydraulic circuit to enable entrapped air and gas to escape therefrom, comprising a casing, a plunger arranged in said casing and having a spiral groove arranged upon its periphery and providing with said casing a restricted passageway for the passage of limited volumes of fluid through said casing, said groove having a cross-sectional area not exceeding .012 square inch, a valve carried by said plunger and adapted to be urged to its seat by fluid pressure in said casing, means resisting the action of said pressure and holding said valve open to enable limited volumes of fluid to pass through said casing in one direction until said pressure reaches a predetermined maximum and overcomes the resistance of said means and forces said valve to its seat to interrupt the passage of fluid through said casing, and another valve carried by said plunger for preventing the passage of fluid through said casing in the opposite direction and adapted to be held closed by 70 said means until a predetermined low pressure has been created in said casing.

2. An air drain valve, for connection into a hydraulic circuit to enable entrapped air and gas to escape therefrom, comprising a casing having 75

a bore and an inlet thereto and an outlet therefrom, a plunger arranged in said bore to control said inlet and said outlet and having a spiral groove formed in its periphery and providing with the wall of said bore a restricted passageway for the passage of limited volumes of fluids through said bore, said groove having a cross-sectional area not exceeding .012 square inch, means for connecting said inlet to a hydraulic circuit to subject said plunger to the fluid pressure in said circuit and cause the same to be moved in said bore by said pressure to a position to close communication between said inlet and said outlet, and a spring normally holding said plunger in a position to close communication between said inlet and said outlet and resisting the movement of said plunger by said pressure and thereby causing said plunger to be reciprocated in said bore to and between said positions as the pressure in said circuit fluctuates.

3. An air drain valve comprising a casing having a bore and an inlet thereto and an outlet therefrom, a plunger arranged in said bore and having a spiral groove formed in its periphery to provide a restricted passageway through said casing, said groove having a cross-sectional area not exceeding .012 square inch, an inlet valve carried by said plunger for controlling said inlet, an outlet valve carried by said plunger for controlling said outlet, means carried by said casing for connecting said inlet into a hydraulic circuit to enable the fluid pressure therein to force limited volumes of fluids through said passageway and to urge said plunger toward said outlet to open said inlet valve and to close said outlet valve, and a spring urging said plunger toward said inlet to hold said inlet valve closed until a predetermined low pressure has been created in said circuit and to hold said outlet valve open until the pressure acting upon said plunger reaches a predetermined maximum.

4. An air drain valve, comprising a casing having means for connecting it to a hydraulic circuit, means providing a restricted passageway of constant capacity for the discharge of limited volumes of fluid from said circuit to an exhaust, said passageway having a cross-sectional area not exceeding .012 square inch, a valve normally closing said passageway to said circuit and responsive to a predetermined low pressure in said circuit for opening said passageway, and another valve responsive to a predetermined high pressure in said circuit for closing said passageway to the exhaust after it has been opened to said circuit by said first named valve.

5. An air drain valve, for connection into a hydraulic circuit to enable entrapped air and gas to escape therefrom, comprising a casing having an inlet and an outlet, means providing between said inlet and said outlet an elongated restricted passageway not exceeding .012 square inch in cross-sectional area and of a length sufficient to limit the flow therethrough to a predetermined low rate at a given pressure, a valve arranged within said casing for controlling the flow of fluid through said passageway, a spring urging said valve to a position to close communication between said inlet and said passageway, said valve member being responsive to a predetermined low pressure to open communication between said inlet and said passageway against the resistance of said spring, and a second valve connected to the first named valve and responsive to a predetermined high pressure to close communication between said outlet and said passageway against further resistance of said spring.

6. An air drain valve, for connection into a hydraulic circuit to enable entrapped air and gas to escape therefrom, comprising a casing having an inlet and an outlet, means providing between said inlet and said outlet an elongated restricted passageway not exceeding .012 square inch in cross-sectional area and of a length sufficient to limit the flow therethrough to a predetermined low rate at a given pressure, a valve arranged within said casing for controlling the flow of fluid through said passageway, a spring urging said valve to a position to close communication between said passageway and said inlet, said valve being responsive to a predetermined low pressure to open said inlet to said passageway against the resistance of said spring, and a second valve connected to the first named valve and responsive to a predetermined high pressure to close said outlet to said passageway against further resistance of said spring.

7. An air drain valve, for connection into a hydraulic circuit to enable entrapped air and gas to escape therefrom, comprising a casing having a bore and an inlet thereto and an outlet therefrom, a valve member fitted in said bore and adapted to be subjected to the pressure at said inlet and having a spiral groove arranged in its periphery and forming with the wall of said bore a restricted spiral passageway for connecting said inlet and said outlet, said passageway having a length sufficient to limit the flow therethrough to a predetermined low rate at a given low pressure, means for connecting said casing to a hydraulic circuit with said inlet in communication therewith, said valve member controlling said inlet and said outlet and communication between said inlet and said groove, a spring urging said valve member toward said inlet to close the same and adapted to permit said valve member to open said inlet in response to a predetermined low pressure in said circuit and to close communication between said inlet and said passageway in response to a predetermined high pressure in said circuit.

8. An air drain valve, for connection into a hydraulic circuit to enable entrapped air and gas to escape therefrom, comprising a casing having a cylindrical bore and an inlet thereto and an outlet therefrom, means providing between said inlet and said outlet a restricted passageway of a length sufficient to limit the flow therethrough to a predetermined low rate at a given pressure, a valve arranged in said casing for controlling the flow of fluid through said passageway, a spring urging said valve to a position to close communication between said inlet and said passageway, said valve being responsive to a predetermined low pressure to open said inlet to the inlet end of said passageway against the resistance of said spring, and a second valve connected to the first mentioned valve and coacting with the wall of said cylindrical bore for closing the inlet end of said passageway against further resistance of said spring in response to a predetermined high pressure.

9. An air drain valve, for connection into a hydraulic circuit to enable entrapped air and gas to escape therefrom, comprising a casing having a cylindrical bore and an inlet thereto and an outlet therefrom, a valve member fitted in said bore and having a spiral groove formed in its periphery to provide with the wall of said bore a restricted passageway of a length sufficient to limit the flow therethrough to a predetermined low rate.

at a given pressure, a valve carried by said valve member for closing said inlet, a second valve carried by said valve member and coacting with the wall of said cylindrical bore for closing the inlet end of said passageway, and a spring urging said valve member to a position to close said inlet, said valve member being responsive to a predetermined low pressure to open said inlet to the inlet end of said passageway against the resistance of said

spring and responsive to a predetermined high pressure to close said inlet end of said passageway against further resistance of said spring.

10. An air drain valve according to claim 8 further characterized by a third valve connected to the other two valves and responsive to a higher pressure for closing said outlet.
